UNITED STATES PATENT OFFICE.

FREDERICK PETRY, OF BROOKLYN, NEW YORK, ASSIGNOR OF ONE-HALF TO LAWRENCE S. HARRISON, OF BROOKLYN, NEW YORK.

SHADE-HOLDING ADAPTER FOR INCANDESCENT ELECTRIC LAMPS.

1,264,124.

Specification of Letters Patent. Patented Apr. 23, 1918.

Application filed September 8, 1917. Serial No. 190,397.

To all whom it may concern:

Be it known that I, FREDERICK PETRY, a citizen of the United States, and a resident of borough of Brooklyn, city of New York, State of New York, have invented a new and Improved Shade-Holding Adapter for Incandescent Electric Lamps, of which the following is a full, clear, and exact description.

10 This invention relates to an incandescent lamp shade holding adapter or to a combined lamp and shade holder and attaching plug especially designed to permit the entire device to be removed as a unit from 15 any standard screw base socket permanently installed so that a vacuum cleaner, heating device or the like can be applied to the socket without the trouble or necessity of loosening the shade-holding screws, as is now commonly the case.

The invention has for its general objects to provide a device of this character which is of comparatively simple and inexpensive construction, reliable and efficient in use, and 25 so designed that the shade and lamp can be detached from a lamp socket just as easily as the removing of a simple lamp.

A more specific object of the invention is the provision of an incandescent lamp 30 adapter so designed as to have permanently attached thereto a shade or shade holder, the parts being so constructed that the adapter can be attached to or removed from a standard screw base socket without taking 35 out the lamp separately or removing the shade.

With such objects in view and others which will appear as the description proceeds, the invention comprises various novel 40 features of construction and arrangement of parts which will be set forth with particularity in the following description and claims appended hereto.

In the accompanying drawing, which 45 illustrates one embodiment of the invention and wherein similar characters of reference indicate corresponding parts in both the views,

Figure 1 is a central vertical section of 50 the device taken on the line 1—1, Fig. 2; and

Fig. 2 is a plan view of the device.

Referring to the drawing, 1 designates 55 the body of the device, which body is preferably made of suitable insulating material

formed with a reduced portion or neck 2. Fitted over the body is a screw base ferrule 3 of conducting material which is adapted to screw into a lamp socket, and on the inner or lower end of this ferrule is screwed a 60 supporting and conducting sleeve 4 which has a reduced portion 5 fitting the neck 2 of the body 1, the lower end of the reduced portion 5 being provided with a thread 6 on which screws the threaded neck 7 of the 65 screw base receptacle 8 into which is screwed the base 9 of an incandescent lamp 10. Passing through the body 1 is a bolt 11 having a nut 12 which forms one terminal of the adapter, the other terminal being formed 70 by the shell or ferrule 3. The head 13 of the bolt is adapted to engage the central contact 14 of the lamp and between the head and body 1 is clamped a metal washer 15 which has interposed between it and the shoulder 75 16 of the receptacle 8 a fiber washer 17. An insulating grip ring 18 surrounds the sleeve 5 and it forms a support for the shade element 19 which has a threaded neck 20 screwed onto the reduced portion of the grip 80 ring 18, said grip ring serving to enable the adapter to be readily handled in applying or removing it. The shade element 19 may take the form of a complete shade or simply a shade holder, as shown in the drawing. It 85 is insulated from the current-conducting parts of the device by the ring 18 and a fiber cup 21 which is clamped between the shoulder 16 and the ring 18, and surrounding the shell or receptacle 8 is a circumferential 90 shoulder 23 on which the cup 21 is seated. In this manner the receptacle 8 is externally protected against grounding.

From the foregoing description taken in connection with the accompanying drawing, 95 the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the 100 scope of the appended claims.

Having thus described my invention, I claim as new and desire to secure by Letters Patent:

1. A device of the class described com- 110

- prising a body of insulation, a screw base ferrule fitted around one end of the body and a screw base receptacle at the other end of the body and connected with the ferrule, a member extending through the body and coöperating with the receptacle to engage the terminals of a lamp and coöperate with the ferrule to engage the terminals of a lamp socket, a shade element and an insulating shell-like body surrounding the receptacle and the lower portion of the first-mentioned body and having a reduced portion with which the shade element is engaged, the shell-like insulating body having a portion extending upwardly from the shade element to form an insulating grip.
2. A device of the class described comprising a body of insulation having a reduced portion, a screw base ferrule on the said body, a sleeve surrounding the reduced portion of the body and having a threaded connection with the ferrule, a screw base receptacle having a threaded connection with the sleeve, a bolt passing through the body and forming a contact coöperating with the ferrule to engage the contacts of a lamp socket, said receptacle having an internal shoulder, washers at the inner end of the body and held by the bolt, with one washer
5. A device of the class described comprising a body of insulation having a reduced portion, a screw base ferrule on the said body, a sleeve surrounding the reduced portion of the body and having a threaded connection with the ferrule, a screw base receptacle having a threaded connection with the sleeve, and a shade element having a threaded connection with the grip ring.
3. A device of the class described comprising a body of insulation having a reduced portion, a screw base ferrule on the said body, a sleeve surrounding the reduced portion of the body and having a threaded connection with the ferrule, a screw base receptacle having a threaded connection with the sleeve, a bolt passing through the body and forming a contact coöperating with the ferrule to engage the contacts of a lamp socket, said receptacle having an internal shoulder, washers at the inner end of the body and held by the bolt, with one washer engaging the shoulder of the said receptacle, a grip ring of insulation surrounding the sleeve, a shade element engaged with the grip ring, a cup-shaped element surrounding the said receptacle and coöperating with the grip ring to insulate the shade element from the receptacle and sleeve, and an insulation ring surrounding the receptacle and interposed between the same and the cup-shaped element.

FREDERICK PETRY.
